Primary Examiner—Stella Reid

(74) Attorney, Agent, or Firm—Thomas M. Gage

(57) CLAIM

I claim the ornamental design for a disposable absorbent article, as shown and described.

DESCRIPTION

FIG. 1 is a left side perspective view of a disposable absorbent article according to our new design.

FIG. 2 is a front elevation of the disposable absorbent article of FIG. 1.

FIG. 3 is a rear elevation of the disposable absorbent article of FIG. 1.

FIG. 4 is a right side elevation of the disposable absorbent article of FIG. 1.

FIG. 5 is a left side elevation of the disposable absorbent article of FIG. 1.

FIG. 6 is a top plan view of the disposable absorbent article of FIG. 1.

FIG. 7 is a bottom plan view of the disposable absorbent article of FIG. 1.

FIG. 8 is a left side perspective view of an alternative disposable absorbent article according to our new design.

FIG. 9 is a front elevation of the disposable absorbent article of FIG. 8.

FIG. 10 is a rear elevation of the disposable absorbent article of FIG. 8.

FIG. 11 is a right side elevation of the disposable absorbent article of FIG. 8.

FIG. 12 is a left side elevation of the disposable absorbent article of FIG. 8.

FIG. 13 is a top plan view of the disposable absorbent article of FIG. 8; and,

FIG. 14 is a bottom plan view of the disposable absorbent article of FIG. 8.

The drawings of FIGS. 1 through 14 are lined for color.

The broken lines shown in the drawings are for illustrative purposes only and form no part of the claimed invention.
